UNITED STATES PATENT OFFICE.

JAMES H. BALDWIN, OF NEW YORK, N. Y., ASSIGNOR TO DULLES-BALDWIN ELECTRIC DRILL COMPANY, OF NEW YORK, N. Y., A CORPORATION OF NEW YORK.

IMPACT MECHANISM.

1,120,360.

Specification of Letters Patent.

Patented Dec. 8, 1914.

Application filed September 23, 1910. Serial No. 583,326.

To all whom it may concern:

Be it known that I, JAMES H. BALDWIN, a citizen of the United States, residing at New York, borough of Manhattan, county and 5 State of New York, have invented certain new and useful Improvements in Impact Mechanism, of which the following is a full, clear, and exact description.

In a common type of rock-drill the hammer or other element which strikes the drill-bit or the chuck carrying the bit is actuated mechanically (in contradistinction to steam or pneumatically actuated devices), the reciprocation of the hammer being effected by 10 a crank on the power-driven shaft. In the operation of the drill the natural result would be to subject the driving mechanism to a severe shock each time a blow is struck. As such shocks are extremely injurious, 15 means have been employed for cushioning the blow with respect to the actuating mechanism, to prevent the full force of the impact from being transmitted thereto. The method usually employed for the purpose is 20 to mount the reciprocating hammer or impact element in an air-cylinder and then connect the cylinder to the operating crank. In this construction the reciprocatory motion is imparted to the hammer through the 25 instrumentality of the air in the cylinder, which air forms a highly resilient or elastic connection between the parts. This scheme is satisfactory as regards cushioning of the blow, but so far as I am aware no means has 30 heretofore been proposed by which the force of the blow upon the drill-bit can be regulated, without varying the speed or rate of the actuating mechanism.

My present invention is therefore de- 35 signed to provide for easy and effective regulation of the blow, and to that end consists in the novel features of construction and combinations of elements hereinafter described, and more particularly pointed 40 out in the appended claims.

A convenient and effective embodiment of the invention, as applied to a rock-drill of the type referred to, is illustrated in the annexed drawing, and referring now thereto, 45 Figure 1 shows the apparatus in longitudinal section. Fig. 2 is a cross section, on line II-II. Fig. 3 is a detail view of the regulating valve and the means for operating the same. Fig. 4 is a longitudinal section 50 illustrating my improved regulating means

applied to a modified type of drill. Fig. 5 is a detail view of the regulating devices employed with said drill. Fig. 6 is a cross section on line VI-VI. Fig. 7 is a longitudinal section illustrating another modification. Fig. 8 is a cross section on line VIII-VIII of Fig. 7. Fig. 9 is a longitudinal section of a further modification. Fig. 10 is a similar section of another modification.

The bit or "steel" (not shown) is carried by a suitable chuck or carrier 1, slidably mounted in the drill casing 2. Similarly mounted in the casing above the chuck is the cushioning air-cylinder or casing 3, and 60 slidable within the same is a piston 4 having a stem 5, the whole constituting the impact element or hammer, extending through the lower or outer cylinder head 6 so as to strike the top of the chuck 1. At its top 65 the cylinder is connected by a pitman 7 to a crank 8 on a driving shaft 9, rotated by any suitable motor, not shown.

In the position of the parts shown in Fig. 1 the hammer has struck a blow on the 70 chuck, and the cylinder or casing 3 is ascending. At first, as the cylinder rises, the hammer remains stationary, creating a partial vacuum above the piston-head 4; but as the cylinder continues to rise the vacuum 75 above the head and the compression of the air below the same become sufficient to raise the hammer and the latter is gradually lifted. As the cylinder passes the upper 80 dead center and begins to descend, the hammer also begins to fall but floats, as it were 85 on the air cushion beneath the piston-head. The increasing downward speed of the cylinder, however, soon equals and then exceeds the speed of the hammer resulting 90 from gravity, so that the force of the cylinder is now exerted downwardly on the piston through the agency of the air above the same. The hammer is thus projected downward 95 against the chuck.

In the preferred construction I provide the cylinder or casing 3 with a valved air-port above the piston, as for example an ordinary "pet cock" such as is shown at 10, 100 for the purpose of regulating the force of the blow, as hereafter described. As the cylinder descends from its upper limit of travel, with the valve open, air will escape through the latter with the result that there 105 will be less compression of the air above the 110

piston, with correspondingly less power exerted, and consequently there will be struck upon the hammer a blow whose power is, in general, dependent upon the extent of opening of the valve.

For the purpose of conveniently manipulating the valve to open and close the same a manually adjustable device 11 is provided, mounted preferably in the side wall of the 10 drill casing. In the form shown this device comprises a small knob or wheel 12 having a stem 14 rotatably mounted in a removable bearing 13 and terminating within the casing is a fork composed of two fingers 15, 16. The plug 17 of the pet cock has a transverse operating pin or bar 18, and the positions of the valve and the operating device are preferably such that with the fork and the pin both perpendicular to the path of 20 the cylinder, as in Fig. 1, the two will just come into contact when the cylinder is at its highest point. It will therefore be seen that if the operating device is turned, placing its fork in an inclined position with respect to the axis of the cylinder, as in Fig. 3, the first engagement of the valve pin with the fork will depress the engaging end of the pin and so turn the valve plug, the extent of movement of the latter being of 30 course dependent upon the adjustment of the fork. Conversely, if the operating device is now restored to its former position the next succeeding engagement will restore the valve plug to the corresponding position. 35 If desired the knob 12 may be provided with a suitable mark, as the notch 20 on its periphery, to indicate the position of the fork.

In apparatus of the type described the capacity of the air-cylinder or air-casing 40 should, for the most efficient operation, be designed with due regard to the weight of the hammer which is to be used; or vice versa. With my invention, however, by which the vacuum and the compression in 45 the cylinder can be regulated, hammers of different weights can be used. This enables me to attach the bit-chuck directly to the hammer or piston; whereas otherwise the different sizes and weights of the bits used 50 in actual work with the drill would at times render the apparatus inefficient. The construction mentioned is illustrated in Figs. 4, 5 and 6. In these figures the stem 5^a is sufficiently long to permit the chuck 25 to be rigidly attached to it, so that the bit or steel 26, mounted in the chuck, will be reciprocated by the piston 4^a as the latter is actuated through the instrumentality of the cylinder 3^a having a head 3^b and the elastic 55 or resilient bodies of air which serve to connect the cylinder and piston operatively together. A single regulating valve, at the upper end (that is, the end adjacent to operating shaft 9^a), is employed. This valve, shown at 17^a, has a transverse operating

member or bar 18^a, provided with a flat face to coöperate with a similarly shaped member 15^a on a stem 14^a rotatably mounted in the drill casing 2^a. For the purpose of adjusting the operating device 70 15^a the stem thereof is provided with a transverse pin 27 on the outside of the drill casing. The cylinder may, if desired, have the usual lateral ports 28. The desired intermittent rotary movement may 75 be imparted to the stem 5^a by the means illustrated in Figs. 4 and 6. For the purpose mentioned the stem, reciprocating in a ratchet-nut 29, is provided with one or more helical or inclined ribs 30, fitting a corresponding groove or grooves in said nut. As the piston is raised the nut is prevented from turning by the pawl 31, and hence the coöoperating ribs and grooves cause the stem to turn; and as the piston descends the nut 85 turns in the opposite direction, bringing the next tooth into engagement with the pawl. In this way the bit or steel is given a slight turn each time it rises.

Another modification is illustrated in 90 Figs. 7 and 8. In this construction the stem 40 which carries the chuck (not shown) is attached to a piston 41 mounted to reciprocate in the drill casing 42. Slidably mounted on the extension 43 of this stem is a cylinder head 44, mounted in the end of a cylinder or casing 45 which is in turn mounted to reciprocate in the drill casing, a resilient body of air being inclosed between the piston 41 and head 44. Fixed on the end of the 95 extension 43 is a piston 46, constructed to reciprocate inside said cylinder or casing 45, and the latter is connected by its end 47 to suitable power-driven reciprocating mechanism, not shown. In the wall of the cylinder, about half-way between the head 44 and the other (open) end, one or more ports 48 are provided, communicating with an enlargement 49 of the inside the drill casing, which enlargement communicates at one end 100 by one or more passages 50 with the atmosphere and by one or more passages 51 with the space between the piston 41 and head 44. 105

From the foregoing it will be apparent that as the cylinder 45 rises the air in the 115 space 52, between the head 44 and the piston 46, will be compressed and the stem 40 lifted, air flowing into the spaces 53, between the head 44 and piston 41, through the passages 51. As the cylinder 45 descends the ports 48 are uncovered, the compression in the space 52 is relieved by the outflow of air through said ports, and air flows out of space 53 through the passages 51; but as the cylinder or casing 45 closes 125 the passages named the air in space 53 begins to be compressed and as the compression increases the piston 41 and stem 40 are thrown downward, with minimum resistance by the air in space 52 since, it will be 130

remembered, the uncovered ports 48 permit free outflow of air to the atmosphere. The force exerted on the piston and stem thus depends upon the compression in the space 5 or chamber 53. For the purpose of regulating this compression, and hence the force of the blow delivered upon the work the casing wall between the piston 41 and the head 44 is formed with a port 54 provided 10 with a suitable valve as for example an ordinary petcock 55, by which the inflow and outflow of air through said port can be regulated, with corresponding variation in the force of the blow, as described in connection 15 with Figs. 1 and 4.

A further modification is illustrated in Fig. 9. Here the reciprocatory cylinder or casing 60 is provided at its ends with outwardly extending flanges 61, 62, fitting the 20 inner surface of the drill casing 63 and spacing the cylinder itself therefrom. At points between the cylinder flanges the drill casing is provided with inwardly extending flanges 64, 65, fitting the outer surface of 25 the cylinder. Three annular spaces or chambers 66, 67, 68, are thus provided around the cylinder. The ends of the cylinder are closed by two heads 69, 70, the latter having a central aperture through which 30 extends the reciprocatory chuck-stem 71, fixed at its inner end to a reciprocatory piston 72 fitting the inside of the cylinder. At each end the cylinder is provided with one or more ports 73, and at an intermediate 35 point one or more ports 74 provide communication between the interior of the cylinder and the annular chamber 67 when the last mentioned ports are uncovered by the piston 72.

40 From the above it will be seen that as the cylinder or casing 60 rises the air in the chamber 75, between the piston 72 and the head 70, and in the annular chamber 68, is compressed, lifting the piston and the stem 45 71. At the same time the air in the chamber 76, above the piston, and in the annular chamber 66, is rarefied, causing air to flow thereinto from the chamber 67 when the ports 74 are uncovered by the upward movement of the cylinder. As the cylinder 50 descends the compressed air in chamber 75 flows out into the annular chamber 68, which, it will be noted, becomes larger and larger as the cylinder moves down. At the 55 same time the port 74, overtaking the piston 72, are closed thereby, and the air in chambers 76 and 66 is compressed, throwing the piston and the stem 71 downward. The force of the blow thus produced depends 60 upon the degree of compression in the chambers 76 and 66 just mentioned, and for the purpose of regulating the compression, and hence the force of the blow, a port 77 is 65 formed in the outer wall of chamber 66, said port being provided with a suitable

valve, as for example the pet-cock 78, by which the inflow and outflow of air through the port 77 can be controlled.

In the construction illustrated in Fig. 10 the air cylinder or casing finds its equivalent in a pair of spaced heads 80, 81, fitting the inner surface of the drill casing 82 and connected by a plurality of tie-rods 83 sliding in suitable grooves 83^a formed in the casing. The head 81 is apertured to permit the 70 chuck-stem 84 to slide therethrough, and at the inner end of the stem is fixed a piston 85 fitting the inside of the casing. The casing wall may be provided with ports 86, in position to be closed and opened alternately 80 by the respective heads. The operation is similar to that of the apparatus shown in the other figures. As the two heads rise the lower port 86 is closed by the head 81 and the air in the chamber 87, between the 85 head 81 and the piston 85 is compressed, air flowing into the chamber 88, above the piston, through the upper port 86. As the two heads descend the upper port is closed by the head 80, resulting in compression in the 90 chamber 88, and as the lower port 86 is passed by the head 81 the compression in chamber 87 is relieved by the outflow of air through the lower port. The piston and stem are thus thrown downward. For the purpose 95 of regulating the compression in chamber 88, and, in consequence, the force of the blow struck by the tool, the upper head may be provided with a suitable valved port, as for example that shown, which is exactly 100 like the device illustrated in Fig. 4.

The method described has proved exceedingly effective in practical use, enabling the operator to vary the force of the blow within wide limits.

105 While I have described the invention as applied to a drill, it may be used in other impact machines in which the hammer or impact element is actuated through the instrumentality of an air cushioning device. 110 It is also to be understood that the invention is not limited to the precise construction shown, by may be embodied in other forms without departure from its proper spirit and scope as defined in the appended claims.

115 I claim:—

1. In an impact mechanism, the combination of a piston, an air-cushion cylinder having a head said piston freely movable in said cylinder, a casing in which the cylinder 120 is axially movable, mechanism for reciprocating the cylinder, an air valve on the head, inside the casing, and means manually actuated from the outside of the casing for controlling said valve.

125 2. In an impact mechanism, the combination of a piston, an air-cushion cylinder having a head in which the piston is freely movable, a casing in which said cylinder is axially movable, mechanism for reciprocating 130

ing the cylinder, an air valve on the head of the cylinder having an operating pin or bar, and a manually adjustable device carried by the casing in position to be engaged by said operating pin or bar as the cylinder reaches the limit of its travel in one direction, whereby to operate the valve according to the adjustment of said device.

3. In an impact mechanism, the combination of a piston, an air-cushion cylinder having a head, said piston freely movable in said cylinder, a casing in which said cylinder is axially movable, mechanism for reciprocating said cylinder, an air valve mounted on said head and means manually actuated from the outside and engaging with said valve as the cylinder is reciprocated whereby the said valve is controlled.

15
In testimony whereof I affix my signature in the presence of two subscribing witnesses. 20
